UNITED STATES PATENT OFFICE

ALFRED MASION, OF BRUSSELS, BELGIUM

BRAKING MECHANISM FOR RAILWAY VEHICLES

Application filed August 10, 1928, Serial No. 298,728, and in Belgium September 9, 1927.

This invention relates to brakes for railway vehicles of the type in which the braking shoes are adapted to engage the side faces of braking wheels or drums instead of engaging the convex peripheral surface of the vehicle wheels as is usually the case. This arrangement is very efficient as it affords the possibility of acting on large braking surfaces in immediate proximity of the axle. 10 However the brakes of this type proposed heretofore require heavy and complicated riggings, and they do not provide for a uniform action of the brake shoes on both sides of the wheel or drum under all operating 15 conditions. The object of the present invention is to obviate these inconveniences.

In accordance with this invention, the brake shoes acting on the side faces of the braking drum or wheel are located above the axle carrying said drum or wheel and are suspended from the vehicle frame by means of pivoted arms or members having their longitudinal axis in the vertical plane extending centrally of the axle. Said arms are 20 actuated by bell crank levers the two arms of which have different lengths so as to amplify as much as possible the pressure transmitted to the brake shoes. The bell crank levers have no operating connection with the 25 shoe carrying arms but they push directly thereon with their short arms, while their long arms are connected by means of rods and a compensating lever with a driving member, for example the piston of a power 30 cylinder.

An important advantage of this construction is that the whole brake gear can be arranged above the axles and as near as possible to the vehicle frame, whereby the bending 35 stresses in its supports are considerably reduced. All the parts for operating the shoe carrying arms can be arranged in the same plane, which is very favourable to the reduction of stresses and provides a very 40 simple and compact structure. Another advantage is that in curves the brake shoes and drum will have the necessary freedom of movement to secure an operative engagement of the braking surfaces even when the 45 braking shoes must move through different 50

distances in order to get into braking engagement with both sides of the drum.

In the accompanying drawing I have diagrammatically illustrated, by way of example, a brake with a friction drum embodying my present invention. 55

Fig. 1 is an elevation at right angles to the vehicle axle in section on line I—I of Fig. 2.

Fig. 2 is an elevation parallel to the axle. 60

Fig. 3 is a horizontal section on line III—III of Fig. 2.

In the drawing 1 is the vehicle frame and 2 an axle on which is secured, at an intermediate point thereof, a drum 3 with side friction surfaces. These side surfaces are adapted to be respectively engaged by two brake shoes 4 located above the axle and carried each by an arm 5 depending from the vehicle frame 1 and having its longitudinal axis in the vertical plane extending centrally of the axle 2. The arms 5 are pivoted to the frame at 6 and the shoes 4 are mounted thereon by means of pin and slot connections 7, 8. Springs 9 are provided between the shoes 4 and links 5 in order to keep said shoes parallel to the friction surfaces of the drum when they are disengaged therefrom. 70

The shoe carrying arms 5 are pushed toward the drum 3 by means of bell crank levers 10 pivoted on vertical pins 11 secured to the vehicle frame 1. The two arms of the levers 10 are of different lengths, and their short arms bear directly against the arms 5, which are preferably provided with yoke shaped members 12 in which these arms are loosely engaged in order to control the returning movement of the shoes to their inoperative positions. To the long arms of the levers 10 are pivoted at 13, rods 14 which are connected by means of a compensating lever 15 to the rod 16 of the piston 17 of an air pressure cylinder 18. 80

When the piston 17 is actuated the two levers 10 turning on their pivots 11 bring the shoes 4 independently of each other into engagement with the sides of the drum 3, whereupon both shoes are pressed against the drum simultaneously and with equal force, even if the axle has moved transversely of 90 95 100

the vehicle frame, as happens in curves of small radius. This is due to the action of the compensating lever 15 and to the fact that the levers 10, not being permanently connected with the arms 5, are free to move through such angle as is necessary to bring the shoes into engagement with the drum.

Upon release of the pressure the arms 5 fall back and are moved out of reach of the drum through the members 12, it being understood however that there should be sufficient clearance between these members and the levers 10 to allow to said levers and to the arms 5 complete freedom of oscillation about their respective pivots 11 and 6 throughout the range of their operative movements.

As shown in the drawing the levers 10 and the parts controlling their operation are preferably mounted in the same plane, so that in comparison with other brake structures the stresses to which they are subjected are reduced, their construction may be made lighter, and they can be firmly mounted on their supports without fear of undue wear. It will also be appreciated that the entire operating gear can be placed very close to the vehicle frame, thus taking up small space, and reducing the length of the pivots 11 subjected to bending stresses.

The construction shown can also be used for braking the wheels 19, but the use of a braking drum as 3 usually is preferable as it does not require that the distance between the axle and the frame be increased.

I claim:

1. In a braking mechanism for railway vehicles, the combination of a shaft, a disc-shaped braking member secured on said shaft, a pair of braking shoes adapted to engage the side faces of said braking member above said shaft, pivoted arms carrying said shoes and adapted to swing in a vertical plane passing through said shaft, and means for actuating said arms comprising levers and rods mounted in a horizontal plane above said shaft.

2. In a braking mechanism for railway vehicles, the combination with a vehicle frame and a vehicle axle, of a disc-shaped braking member secured to said axle, a pair of braking shoes adapted to engage the side faces of said braking member above said axle, a pair of arms each carrying one of said shoes, said arms being pivoted to said frame for motion in a vertical plane, and means for moving said arms towards said braking member, said means being located in a horizontal plane above said axle.

3. In a braking mechanism for railway vehicles, the combination with a vehicle frame and a vehicle axle, of a braking drum on said axle, a pair of vertical arms pivoted to said frame, braking shoes horizontally pivoted on the free ends of said arms, said braking shoes

being adapted to engage the side faces of said drum above said axle, bell crank levers for actuating said vertical arms, a power cylinder secured to said frame, a piston in said cylinder, and lever and rod connections between said piston and said bell crank levers, said piston, bell crank levers and connections being located in a horizontal plane above said axle and in close proximity to said frame.

In testimony whereof I affix my signature.

ALFRED MASION.
